UNITED STATES PATENT OFFICE.

JAMES E. MULCAHY, OF CLEVELAND, OHIO.

PACKING CASE.

Application filed February 12, 1923. Serial No. 618,504.

To all whom it may concern:

Be it known that I, JAMES E. MULCAHY, a citizen of the United States, residing at Cleveland, in the county of Cuyahoga and 5 State of Ohio, have invented a certain new and useful Improvement in a Packing Case, of which the following is a full, clear, and exact description, reference being had to the accompanying drawings.

10 This invention relates to cases which are adapted for shipping heavy articles wherein the principal dimension is the length, such as pressed steel frames, structural steel sections, and the like.

15 Usually pressed steel frames such as the side bars of an automobile frame are manufactured in one place and are then shipped to another place for assembly. The packing of these frames has hitherto been a 20 serious problem in view of the fact that the usual shipment weighs about three thousand pounds. Accordingly, if the case housing these frames should be dropped even a short distance or if the case should 25 be swung against a solid object, the corners are apt to be displaced with consequent damage to the freight. Numerous types of cases have been tried to overcome this difficulty, but heretofore no satisfactory case 30 has been devised.

One of the objects of my invention therefore, is to provide a packing case which is capable not only of satisfactorily withstanding hard usage incident to the handling of 35 the class of freight above described, but also to provide a case which may be readily assembled by unskilled labor. In addition, my invention contemplates a packing case having a smooth exterior which permits one 40 case to be closely packed adjacent another, thus facilitating the storage thereof in railway cars, steamships and warehouses, and which also serves as a protective measure for preventing various parts of the box from 45 being turned out of place with subsequent damage to the freight while in transfer.

I carry out the above objects by providing 50 a case which comprises an inner and outer container which are preferably complementary shaped and in close fitting engagement with each other. The inner container is made of comparatively heavy stock, and the various walls thereof are so positioned 55 with relation to the other walls that the case is prevented from collapsing either

longitudinally or transversely thereof while in use. The outer container comprises a sheeting of comparatively light stock and is also so formed as to prevent collapsing of the case. The inner container may be 60 constructed apart from the outer container, but I prefer to make each wall thereof by reinforcing the corresponding wall of the outer container whereby when the walls of the outer container are placed in juxtaposition, the reinforcement forms the inner container. 65

The preferred form for carrying out the above objects will be hereinafter set forth in the following description which pertains 70 to the accompanying drawings while the essential features will be summarized in the claims.

Fig. 1 is a perspective view of a packing case constructed according to my invention 75 and having a portion thereof broken away to show the inner construction; Figs. 2 and 3 are side and end elevations respectively of one wall; Fig. 4 is a vertical longitudinal section taken through the case; Fig. 5 is 80 a transverse section taken through the case; Figs. 6 and 7 are side and end elevations respectively for another wall of the case; and Figs. 8 and 9 are plan and end elevations respectively of the top and bottom 85 walls of the case.

In the preferred form, my invention embodies a case having an inner and an outer container, so formed that the inner container comprises reinforcement on the walls of the 90 outer container. Accordingly, the case when assembled comprises a six-sided figure, wherein 10 and 11 constitute the top and bottom walls, 12 and 13 the side walls, and 14 and 15 the end walls respectively. To 95 facilitate production, the opposed walls are similarly constructed, and moreover the reinforcement is so positioned that when the parts are assembled, substantially all lifting stresses are transmitted directly to the reinforcement. 100

The top and bottom walls being identical, reference may be had to Figs. 8 and 9 wherein only one wall is shown. This wall comprises a rectangular member comprising 105 sheathing 20 secured upon an open frame which is spaced inwardly from the marginal edges of the wall. This frame comprises a pair of longitudinal members 21 which are connected by transverse members 110

22, shown particularly in Fig. 1. Suitable corner braces 23 and transverse braces 24 may be employed as shown in Fig. 8 for reinforcement purposes. The members comprising this frame are preferably squared stock considerably thicker than the sheathing secured thereto.

In Figs. 2 and 3, the side 12 is also shown as a rectangular unit comprising sheathing 25, which is secured preferably to a one-piece reinforcing member 26. The member 26 may extend the entire length of the wall but the width of the member is less than that of the wall so as to provide shoulders 15 against which the opposed faces of the members 21 of the top and bottom frames may engage. The reinforcement 26 may comprise a plurality of narrow strips placed side by side, but I prefer to use a single board because of the fact that this has been found to produce the most satisfactory results. In Figs. 6 and 7, the wall 14 is also shown as rectangular in form and formed of sheathing 27 secured to a reinforcing member 28. The width of the end walls is preferably the same as that of the side walls, while the width of the reinforcement 28 is the same as that of the reinforcement 26 on the side walls. As shown in Fig. 6 however, the reinforcement 28 terminates short of the ends of the wall, thus providing a space against which the ends of the side walls and associated reinforcement may engage.

35 When the case is assembled as shown in Figs. 1, 4 and 5, the reinforcement on the side and end walls rests upon the reinforcement of the bottom wall and is engaged by the reinforcement of the top wall. This in effect provides a very rigid inner container having solid side and end walls and having fabricated top and bottom walls which serve to carry the load stresses, and thus to prevent damage to the freight if the load is shifted. This construction provides a satisfactory container for shipping freight of great weight and comparatively small volume. Since the outer container is formed complementary to the inner container, 40 additional protection is provided against collapsing in a direction longitudinally or transversely of the case. Moreover, the sheathing provides a smooth exterior which facilitates the storage of cases in warehouses, platforms and transportation vehicles.

45 I claim:—

1. A packing case comprising complementary six-sided inner and outer containers, the outer container having a smooth walled exterior, some of the walls of the inner container being parallel to and contiguous with the adjacent walls of the outer container

and the inner container having a pair of opposed uninterrupted end walls.

2. A packing case comprising similarly shaped inner and outer containers, the outer container having a smooth walled exterior, and the inner container having open similarly formed top and bottom walls and having a pair of closed walls disposed therebetween, the closed walls being fastened together in such manner that the adjacent walls of the inner and outer containers are contiguous.

3. A packing case comprising an inner and an outer six-sided container having the adjacent walls thereof in engagement with each other, the outer container having a smooth exterior, and the inner container having a fabricated top and bottom and having smooth side and end walls, said last mentioned walls being contiguous with the walls of the outer container.

4. A packing case having top and bottom, side and end walls, the top and bottom walls overlapping said walls and having a reinforcement disposed on the inner faces thereof, said reinforcement being spaced inwardly from the marginal edges thereof, each of said walls having a continuous and contiguous reinforcing member at the inner face thereof, said member being in engagement with the reinforcement on the top and bottom respectively.

5. A packing case having top, bottom, side and end walls, the top and bottom having longitudinal and transverse reinforcing members on the inner face thereof, said member being spaced inwardly from the marginal edges of the top and bottom respectively, the side walls having a continuous reinforcing member extending longitudinally thereof and of less width than the side walls, the top and bottom edges of said last mentioned member being disposed intermediate the opposed faces of the longitudinally extending reinforcing members of the top and bottom walls respectively, and the vertical face of said member being contiguous with the adjacent side walls.

6. A packing case having top and bottom side and end walls, the top and bottom walls having reinforcement on the inner faces thereof, each of the side walls having a reinforcing member extending longitudinally thereof and each of the end walls having a one-piece reinforcing member contiguous with the inner faces thereof, the top, bottom and vertical edges of said members being in engagement with the opposed faces of the reinforcement on the top, bottom and side walls respectively.

In testimony whereof, I hereunto affix my signature.

JAMES E. MULCAHY.
